UNITED STATES PATENT OFFICE.

JAMES J. GILMORE, OF ALLEGHENY, PENNSYLVANIA.

BINDER.

SPECIFICATION forming part of Letters Patent No. 602,742, dated April 19, 1898.

Application filed March 20, 1897. Serial No. 628,435. (No model.)

To all whom it may concern:

Be it known that I, JAMES J. GILMORE, of Allegheny, in the county of Allegheny and State of Pennsylvania, have invented a new and useful Improvement in Binders, of which the following is a full, clear, and exact description, reference being had to the accompanying drawings, forming part of this specification, in which—

10 Figure 1 is a perspective view of my improved binder. Fig. 2 is a transverse section through the clamping device. Fig. 3 is a bottom plan view of the clamp detached and disconnected. Fig. 4 is a side elevation of a modified form, and Fig. 5 is a top plan view thereof.

15 My invention relates to that class of temporary binders in which the upper board thereof is retained in operative position by means of clamps and is designed to afford a simple and effective device therefor.

In the drawings, 2 is the lower or stationary board, having thereon the stationary clamping-bar 3.

20 25 4 4' are rods extending from the bar 3 and fixed thereto.

5 is the upper or movable board, having thereon a clamping-bar 6, provided with holes to permit of the passage of rods 4 4' there-

30 through.

7 7' is the spring-clamp, having upwardly-extending handpieces 8 8'.

35 9 are notches in the ends of the clamp 7 7', designed to impinge upon the rods 4 4' and serving as guides to keep said clamp in alignment therewith.

In Figs. 1, 2, and 3 I show the clamp 7 7' in its preferred form, wherein it is represented as being constructed of flat strips or 40 clamping-arms of metal fixed at opposite ends to the clamping-bar 6 by rivets 10 and adapted to contact with at the end and securely grasp the rods 4 4'. In order to bring the notches of the clamp 7 7' in alignment with 45 the rods 4 4', I preferably cut away portions of said clamp 7 7', as shown in Fig. 3, and I preferably construct the handpieces, as shown, by securing angled strips to the clamps 7 7', near the ends thereof.

50 In Figs. 4 and 5 I show a modified form of

my device, wherein the clamp is represented as two L-shaped strips or arms 7^a and 7^b, pivoted at 11 and having between parts 8 8' the expansion-spring 12, adapted to force the ends of the clamp into engagement with the 55 rods 4 4'. The clamping-bar 6 is herein shown as of trough-shaped construction adapted to carry the pivots 11, as shown in Fig. 5.

The operation of my device is as follows: The upper or movable board 5, carrying the 60 clamping-bar 6 and spring-clamp 7 7', being removed from the rods 4 4', the papers are placed upon the lower or stationary board 2 and clamping-bar 3, the rods 4 4' being inserted through holes provided in said papers. 65 The upper or movable board 5 is then replaced, as shown, and pressed down upon the papers, the notches 9 in the clamp 7 7' sliding upon the rods 4 4' and held in close contact therewith by the spring of said clamp, thus resisting any upward pressure that may be exerted thereon. When the papers are to be removed or additional papers are to be bound thereon, the handpieces 8 8' are compressed by the thumb and finger, whereby the ends of the 70 clamp 7 7' are withdrawn from contact with the rods 4 4', permitting the upper clamping-bar 6 to slide freely upon said rods.

The advantages of my invention will be appreciated by those skilled in the art to which 80 it relates. To the manufacturer it presents an effective device that is easily and cheaply constructed and to the user one that is easily and quickly operated with one hand. Its parts being few in number and of simple construction, it is not liable to get out of order nor is its operative action liable to fail.

The form and size of the boards 2 and 5 may be altered to suit especial requirements or may be entirely omitted, the clamping-bars 90 3 and 6 acting with equal efficiency. Nor do I confine myself to the relative proportions of the parts of my device as shown, since they may be varied as may be desired. Other changes will suggest themselves to the skilled 95 mechanic and may be made without departure from my invention, since

I claim—

In a temporary binder, having clamping-bars and upright rods, the combination there- 100

with of oppositely-extending clamping-arms, bearing on the rods and adapted to hold the clamping-bar, and a handpiece on each of said arms at a point between said rods, the 5 handpieces of said arms being adapted to be moved simultaneously on compression by the hand and to release the pressure on said rods.

In testimony whereof I have hereunto set my hand.

JAMES J. GILMORE.
